[57] **CLAIM**

The ornamental design for a frame for a facsimile bin, as shown and described.

DESCRIPTION

FIG. 1 is a front elevational view of a frame for a facsimile bin showing our new design;

FIG. 2 is a rear elevational view thereof;

FIG. 3 is a top plan view thereof;

FIG. 4 is a bottom plan view thereof;

FIG. 5 is a side elevational view thereof, the opposite side being a mirror image; and,

FIG. 6 is a rear, top left side isometric view thereof, the broken line drawing of a facsimile bin is for illustrative purposes only and forms no part of the claimed design.

FIG. 1

FIG. 2
